UNITED STATES PATENT OFFICE.

GEORGE BROWN SINCLAIR AND SILAS E. MENOUGH, OF WELLSVILLE, OHIO, ASSIGNEES,
DIRECT AND MESNE ASSIGNMENTS, TO THE UNIVERSAL VACUUM SEAL COMPANY, OF WELLSVILLE, OHIO.

DOMESTIC VACUUM-SEALER.

1,145,810.

Specification of Letters Patent. Patented July 6, 1915.

Application filed October 25, 1913. Serial No. 787,835.

To all whom it may concern:

Be it known that we, GEORGE BROWN SINCLAIR and SILAS E. MENOUGH, citizens of the United States, and residents of Wellsville, in the county of Columbiana and State of Ohio, have invented a new and Improved Domestic Vacuum-Sealer, of which the following is a full, clear, and exact description.

This invention relates to the art of preserving and has particular reference to the preservation particularly of food stuffs by what is commonly known as the vacuum process.

Among the objects of the invention is to provide a simple, convenient, easily manipulated and reliable device for domestic use for the preservation of fruits, meats, fruit juices, milk or the like, in airtight receptacles or packages.

More specifically stated we provide a hand operated machine including an air pump, a vacuum hood connected with the pump by a flexible tube, an adjustable stem carrying the hood, and means to control the various positions of the stem and parts associated therewith, and whereby we obtain a quick and easy operation.

The foregoing and other objects of the invention will hereinafter be more fully described and claimed and illustrated in the drawings forming a part of this specification in which like characters of reference indicate corresponding parts in all the views, and in which—

Figure 1 is a front elevation of a machine made in accordance with this invention, parts being in section; Fig. 2 is a side elevation of the same looking toward the left in Fig. 1; Figs. 3 and 4 are detailed views of auxiliary devices described below; and Fig. 5 is a detail of the sealing mechanism.

The several parts of the device may be made of any suitable materials, and the relative sizes and proportions, as well as the general design of the mechanism, may be varied to a considerable extent without departing from the spirit of the invention hereinafter more fully set forth and specifically claimed.

A machine made in accordance with this invention comprises a base 10 adapted to support the machine in upright position in any convenient place as upon a table or stand. The construction herein illustrated being adapted to be supported for use upon

a table, bench or stand, is of a very different character from devices heretofore proposed for accomplishing the same purpose. In other words, the mechanism is of a small, compact and comparatively inexpensive nature adapting it not only for the performance of thoroughly reliable service, but also for use in practically every household. Being of a small and compact design when not in use, it may be placed upon an upper shelf or some other out-of-the-way place where it will occupy a minimum amount of space. A standard comprising a plurality of columns 11 connected by a cross head 12 is supported upon a foot piece 13 upon the base 10. The foot piece is provided at its center with a disk-like support 14 for any suitable size or form of package 15 to be sealed and located between the columns 11. The height of the cross head 12 is sufficient to accommodate any ordinary size of receptacle or package for the purposes of this invention.

At the center of the cross head is a hub 16 having a vertical bore in which is slidably fitted a stem 17. The stem carries at its lower end a hood 18 of inverted cup-like construction provided at its lower edge or rim with a packing gasket 18' of cork, rubber or the like, whereby a substantially airtight connection is made between the hood and the upper portion of the package 15, as shown in Fig. 1, the mouth of the package coming within the hood. The stem 17 is preferably hollow and is adapted to be temporarily fixed with respect to the hub 16 by means of a winged screw 19 acting through the front wall of the hub.

At 20 we show an air pump, the cylinder of which is pivoted at 21 upon a pair of bearings 22 connected to the base 10 and adapted to oscillate around a horizontal axis extending transversely of the machine just in the rear of the standard. The piston rod 23 of the pump is pivoted at 24 to an oscillating hand lever 25 pivoted at 26 to a bracket 27 likewise secured to the base 10, but in front of the hub. The lower end of the pump cylinder is connected by means of a flexible tube 28 to the vacuum hood 18, said tube communicating with the upper portion of the interior of said hood, as shown in Fig. 1. The hood also is provided with a pet cock 29, and at another point there communicates with the interior

2
of the hood a rigid tube 30 carrying at its upper end a vacuum gage 31.

The hollow stem 17 is fitted with one or more thimbles or nuts 32 through which 5 operates in a substantially airtight manner a plunger screw 33 having a head 34 at its upper end above the end of the stem. Said screw at its lower end is connected in any suitable manner with a plunger head 35. 10 The stem is also provided at its upper end with a knurled head 17' to facilitate the manipulation of the stem independently of the plunger.

The disk support 14 is tapped at its center, as shown at 14', to receive the threaded stud 36 of a pedestal 37 shown in Fig. 4. Said pedestal may be of any suitable construction or size and is adapted to be used during the sealing of small packages such 20 as jelly glasses or the like, and the pedestal likewise may be tapped as indicated at 37' to receive a threaded stud 38 of an auxiliary vacuum cup 39 shown in Fig. 3. The vacuum cup, however, may be connected directly 25 in the socket 14', if desired, without using the pedestal. In the sealing of packages, such as jelly glasses, shown in dotted lines at 40, having outside caps 41, the special cup 39 is used for coöperation with the 30 lower rim of the vacuum hood 18, the vacuum cup being of a strong substantial nature and having a shoulder 39' corresponding substantially in form and size to the shoulder 15' of the standard package shown 35 in Fig. 1.

From the foregoing description of the mechanism, its manner of use may be briefly described as follows: With reference especially to Fig. 1, with the pet cock 29 closed 40 and with the hood fitted to the top of the shoulder 15' of the package 15 independently of the permanent sealing means therefor, as herein shown, the screw 19 will be set to lock the stem and hood as shown. 45 The gasket 18' will afford a substantially airtight connection between the hood and the outside of the package. The package cap 15^a or permanent sealing means for the package 15 will be set loosely upon the sealing gasket 15^b upon the shoulder 15^c, the 50 plunger head 35, however, not being under pressure upon the cap 15^a. Two or three strokes of the lever 25 will suffice to cause from twenty to twenty-two inches of vacuum to be indicated by the indicator 31 55 through the action of the pump 20. The vacuum above indicated will serve to make a corresponding vacuum at the top of the

contents of the package 15 and upon turning down the screw 33 the plunger head 35 60 will cause the cap 15^a to be firmly seated in its place, and upon opening the pet cock 29 so as to restore the interior of the hood to atmospheric pressure, such pressure will act to permanently hold the cap 15^a sealed. 65 The plunger screw will now be lifted from the cap and the stem 17 with the hood attached thereto will be lifted so as to remove the sealed package and admit another to be sealed. 70

The above described operation will be understood as applying substantially to the treatment of packages with outside caps in connection with the auxiliary cup 39. In this operation the vacuum within the hood 75 18 serves to exhaust the air from the interior of the cup and in other respects the action is quite similar to the action upon such receptacles as shown at 15.

Having thus described our invention, we 80 claim as new and desire to secure by Letters Patent:—

The herein described portable domestic vacuum sealer comprising, in combination, a base adapted to rest in use upon a table or 85 the like, a standard supported upon and above the base and including a disk at the bottom of the standard and a cross head at the top of the standard, there being provided space between the cross head and the 90 disk to accommodate a package to be sealed, said cross head including a hub having a smooth vertical bore, a vacuum hood adapted to make airtight connection directly with the package aforesaid independently of the 95 permanent sealing means therefor, means adjustable vertically through said hub to control the movements and position of the hood, a plunger acting through said vertical adjustable means and into the hood independently of the means for controlling the hood, an air pump supported upon and above said base, and a flexible tube connected directly between the pump cylinder and the interior of said hood, all of said 100 mechanism constituting a self-contained machine and movable as such to any desired place for use or storage.

In testimony whereof we have signed our names to this specification in the presence 110 of two subscribing witnesses.

GEORGE BROWN SINCLAIR.
SILAS E. MENOUGH.
